INCINERATION OF WASTE MATERIALS

Frederick B. Schilling, Bayside, N. Y., assignor to
 Nichols Engineering & Research Corporation,
 a corporation of Delaware

Application September 14, 1936, Serial No. 100,610

8 Claims. (Cl. 110—12)

This invention relates to the incineration of waste materials and is particularly adapted for use in connection with the process and apparatus as disclosed in the patent to Dudley Baird and 5 Robert W. Rowen, No. 2,015,050, granted September 17, 1935.

The objects of this invention include the provision of a process and apparatus for drying and incinerating waste products such as sewage materials with a high degree of efficiency so that little or no extraneous fuel need be used and at the 10 same time eliminating obnoxious odors from the evolved gases and vapor.

Various further and more specific objects, features and advantages will clearly appear from the detailed description given below taken in connection with the accompanying drawings which form a part of this specification and illustrate merely by way of example preferred forms of the apparatus of the invention.

The invention consists in such novel features, arrangements and combinations of parts as may be shown and described in connection with the apparatus herein disclosed, and also such novel 25 methods and combinations of method steps as are disclosed and described herein.

In the drawings, Fig. 1 is a sectional view of a furnace structure, together with certain auxiliary apparatus somewhat schematically indicated, arranged for carrying out the invention in its preferred form; and

Fig. 2 is a view similar to Fig. 1, but illustrating an alternative embodiment of apparatus for carrying out the invention in certain of its phases.

In Fig. 1 a multiple hearth furnace structure is shown at 5. This furnace if desired may be similar in construction to that shown in greater detail in the above mentioned patent. It may be provided at its top portion with an intake hopper 6 equipped with a suitable feeding device as at 7 which seals the inlet against escape of gases or vapor at that point. A discharge outlet for the ash resulting from the incineration process, may be provided at the bottom of the furnace as indicated at 8. Fuel burners as at 9 may be mounted to project a flame into the furnace at various points, but with the equipment and process hereinafter described, these burners will ordinarily not be necessary except in bringing the furnace 50 structure up to temperature when starting the incineration operation or when burning material of unusually high water content. The several hearths within the furnace are indicated at 11 to 17 inclusive, alternate hearths respectively being 55 provided as shown with peripheral and central

discharge openings, permitting the material being dried and incinerated to be rabbled over each hearth and from hearth to hearth down through the furnace while it is first dried on the upper hearths and later incinerated on intermediate 5 or lower hearths, the resulting ash being allowed to become somewhat cooled on the lower hearth before it is discharged through outlet 8. The hearths are supported within a furnace wall 18.

The rabbelling structure may comprise a central 10 rotatable shaft 19 carrying a plurality of rabble arms as at 20, cooperating with each of the several hearths. The shaft may be rotated in the manner disclosed in the above mentioned patent and the shaft and rabble arms may also preferably be provided with interconnected cooling air conduits as disclosed in said patent, whereby a supply of air from blower 21 is passed through such conduits, thereby maintaining the rabbelling structure at a temperature low enough to prevent 15 injury thereof in the presence of the relatively high temperatures within the furnace. This cooling air in flowing through the rabbelling structure, becomes preheated and may be drawn off as through a conduit 22 and forced as by a fan 23 20 through conduit 24 into a recuperator 25. As 25 through conduit 24 into a recuperator 25. As hereinafter explained, this air may become further preheated in the recuperator and may then be introduced at one or more of the lower 30 hearths of the furnace, as through a conduit 26. Thus a supply of preheated air is made available 30 for efficient combustion at the incineration hearths of the furnace. The amount of this air may be adjusted by adjusting the speed of the fans 21 and 23.

Within the furnace and for example at hearths 14, 15 and 16, the incineration of the waste material will be effected in the presence of a counter-current stream of preheated air and evolved gases rising up through the furnace. This counter-current stream may finally be largely withdrawn 40 through an exit opening 27, located for example above hearth 13. The temperature conditions within the furnace are preferably so arranged that the exit gases passing through outlet 27 will 45 be at a temperature of 1100° F. or higher, which will ordinarily be sufficient to insure substantial elimination of noxious odors in such gases.

From the outlet 27 the exit gases may be forced as by a fan 28, through conduits 29 with 50 in the recuperator 25, whereby such gases are brought into heat interchanging relationship with the intake air for the furnace for pre-heating the latter. Sufficient heat may be efficiently absorbed from the exit gases within the 55

conduits 29 so as to bring their temperature down to in the neighborhood of from 750 to 850° F., whereupon such gases may be conducted out through conduit 30 connected as shown to the 5 stack. The fan 28 under some conditions may be unnecessary, particularly if the stack or equivalent suction device is such as to withdraw the gases at a desired rate through the recuperator.

10 Apart from the upper furnace hearths 11 and 12, it will be noted that the apparatus as thus far described, is similar to that of the above mentioned Patent No. 2,015,050. However, in order to more efficiently utilize the fuel value of the 15 burning waste material and to avoid loss of the useful heat in the exit gases passing through conduit 30, I have provided means for passing a part or all of such gases over one or more preliminary drying or prewarming hearths at the 20 top of the furnace. In this way the exit gases available in conduit 30 at a temperature in the neighborhood of 800° F. for example, may be brought into heat exchanging relationship with the cold wet waste material entering the furnace, and thus enough of the heat of the exit 25 gases may be absorbed by the wet material to bring the temperature of the gases down to in the neighborhood of 350 to 400° F. for example, before they are discharged to the stack. In this 30 manner most of the useful heat which it is economical to recover from the exit gases, may be reabsorbed within the furnace so that the waste material even though it may have from 65 to 70% moisture for example, may be safely incinerated within the furnace without the use of the fuel burners or other extraneous fuel and without discharge of noxious gases from the apparatus.

35 The particular apparatus shown in Fig. 1 for accomplishing these objects, may comprise a branch conduit 31 communicating with conduit 30 for conducting the exit gases to one or more furnace inlets, as at 34 and 35, communicating with the spaces over hearths 11 and 12 for example. The hot waste gases may pass over the relatively cold wet material on these hearths and thence through exit openings as at 36 and 37, conduit 38, fan 39 and conduit 40, back to the stack connection.

40 The proportion of the exit gases which it is desired to by-pass over the top hearths (if it is not desired to pass all of such gases over these hearths) may be regulated by adjusting dampers as at 31' and 33'. Under some circumstances the exit gases from conduit 30 may be at an excessively high temperature such as might cause scorching of the waste material on the top hearths, with the consequent undesired production of odoriferous gases at this part of the furnace. To avoid this result, some air at room 45 temperature may be introduced into the conduit 31' through a conduit 32 and damper 32', to lower the temperature within conduit 31' to the desired degree. The relative proportions of the hot exit gases which are reintroduced into the furnace over hearths 11 and 12 respectively, may be adjusted by means of dampers 34', 35', 36' and 37'. A relatively large portion of the exit gases may be passed over hearth 11 without danger of 50 scorching the material thereon since at this hearth the material is relatively cold and wet. If it is found that the material on hearth 12 is being raised to a temperature such as to tend to cause scorching and odors, the amount of the 55 hot gases introduced over this hearth may be

readily reduced by partially closing dampers 35' and 37'. However, the hot exit gases being largely inert, will tend to retard combustion of the waste material on the upper drying hearths even though the material may be of low moisture 5 content.

Thus on the top hearth 11 the waste material may be warmed to a considerable extent and the drying process initiated through utilization of heat which would otherwise be wasted. This 10 warming and drying action may continue to a further degree on hearth 12 and if desired, one or more additional drying hearths might also be provided with heat in the same manner as hearths 11 and 12. With the particular example shown, the drying action may be largely completed on hearths 13 and 14 so that combustion 15 may begin on these hearths and proceed to completion with the substantial elimination of all organic matter of the waste material at the 20 lower hearths.

In cases where the incoming waste material may be particularly dry so that the burning might be initiated on one of the top hearths, the exit gases may be passed directly to the stack 25 without being reintroduced into the furnace at the drying hearths. Then in such cases, the possibility of passing obnoxious gases resulting from scorching the material, out through conduit 38 may be avoided by closing dampers 34' to 37'. 30 Thereafter any obnoxious gases and vapor evolved from the top two hearths, may pass down and out in admixture with the hot gases through conduit 27 so that the odors are eliminated.

35 Since in the furnace as above described when operated in its preferred way, the hearths 11 and 12 are used as prewarming or drying hearths, such hearths may be constructed of metal as indicated, instead of using the refractory material 40 practically necessary for the lower high temperature hearths as shown. In cases where incineration will be initiated, for example on part of hearth 12, this hearth may also preferably be made of refractory material. The use of metal 45 top hearths permits more ready access of heat by conduction to the under surfaces of the layers of waste material on these hearths, thereby increasing the speed of drying.

50 In the embodiment of the invention illustrated in Fig. 2, many of the parts may be similar to those above described and are accordingly identified by like reference numerals. As shown in this embodiment, an additional drying hearth 13' is used. The waste material passes over the various hearths and down through the furnace in a manner similar to that above described in connection with Fig. 1, and the preheated intake air for supporting combustion is similarly introduced through conduit 26. The countercurrent 55 stream of air and gases in Fig. 2, however, is preferably withdrawn through an outlet conduit 50 from substantially the hottest area within the furnace, the rate of withdrawal being regulated by adjustment of the damper 50'. The vapor 60 evolved from the drying material on the upper hearths may be passed downwardly in the drying portion of the furnace along the direction of movement of the waste material and out through a discharge conduit as at 51 having a regulating 65 damper 51'. The hot outlet gases from conduit 50 meet the relatively cooler vapor from conduit 51 and may be mixed therewith for example in a chamber 52. Usually after the process has gotten 70 under way, the exit gases from conduit 50 will 75

- be at a temperature sufficiently high above 1100° F. so that the resulting mixture within chamber 52 will be at a temperature sufficient to destroy odors of the vapor coming through conduit 51.
- 5 If under special circumstances there is danger of this temperature not being sufficient to destroy odors in the gas and vapor mixture, the chamber 52 may be provided with a fuel burner as at 53. Ordinarily, however, it will be unnecessary to use this burner except when starting the process. The gas and vapor mixture passes from chamber 52 through conduit 54 into conduits 55 within the recuperator 25, and thence through conduit 56 to a stack connection. A part of this gas if 10 desired may be by-passed through a conduit 57 and conduits 58 and 59 into the space above the top hearth of the furnace. The portion of the gases thus by-passed may be regulated by adjustment of dampers 56' and 57'.
- 20 Thus a supply of hot waste gases mixed with some vapor is reintroduced over the top drying hearths of the furnace and since this mixture will contain only a relatively small quantity of air, there will be little or no tendency for the waste 25 material to start to burn on the upper hearths. Yet the temperature of the gas and vapor mixture will be such as to insure efficient drying on these upper hearths, thereby placing the material in such condition that it will be rapidly, efficiently 30 and thoroughly incinerated in the lower portions of the furnace. And the serious odors of the gaseous products of combustion evolved from the incineration hearths will be substantially eliminated because of the withdrawal of such gases 35 through the hottest area of the furnace. The less serious odors of the vapor evolved from the drying hearths will be eliminated as a result of mixture of such vapor with said hot exit gases, yet without bringing the vapor into the 40 incineration areas of the furnace which would tend to blanket the fire. It will be noted that the arrangement provides for recirculation through the drying portion of the furnace of a considerable part of the hot inert exit gases. This makes 45 possible an efficient drying action without introducing an excess of preheated air into the furnace beyond what is necessary for combustion purposes, plus a factor of safety. This in turn avoids the necessity of preheating as large a supply of intake air as might otherwise be required 50 to insure an adequate stream of gases and air to quickly dry and burn the material treated.
- 55 While the invention has been described in detail with respect to particular preferred examples, it will be understood by those skilled in the art after understanding the invention, that various changes and further modifications may be made without departing from the spirit and scope of the invention, and it is intended therefore 60 in the appended claims to cover all such changes and modifications.
- 65 What is claimed as new and desired to be secured by Letters Patent is:
1. Process of drying and incinerating waste material to form an ash substantially free of organic matter and evolved gases free of noxious odor, which comprises passing such material successively through a plurality of zones, temporarily retaining said material in substantially horizontal layers at each of said zones while periodically agitating it and causing it to be broken into fine pieces and maintaining it in finely divided condition while advancing it through each zone and gradually from zone to zone, preliminarily warming the material in the first zone or 70 zones, then drying the material in a succeeding zone or zones, then burning the material in a subsequent zone or zones, such drying and burning being conducted in the presence of a stream of preheated air passed countercurrent to the passage of the material and including gaseous products of combustion and vapor evolved from the drying and burning material, withdrawing said stream from a drying zone, then bringing such stream before any substantial cooling thereof, into heat exchanging relationship with a supply of air to provide said preheated air, thereafter absorbing further heat from said withdrawn stream by passing at least a substantial part thereof into contact with the material at 15 said preliminary warming zone or zones, and then discharging such part from said warming zone or zones independently of said withdrawal of gases from the drying zone.
  2. Process of incinerating waste material, which comprises preliminarily warming, drying, and burning the material by passing the same through a plurality of zones in succession, effecting said drying and burning operations in the presence of a stream of air together with gaseous products of combustion and vapor evolved from the drying and burning material, withdrawing said stream from said zones and bringing the same into heat exchanging relationship with a supply of said air for preheating the latter before introduction into said burning and drying zones, thereafter absorbing further heat from said withdrawn stream by passing at least a substantial part thereof into contact with the material at the preliminary warming zone, and then discharging such part from the warming zone independently of said withdrawal of the gaseous stream from succeeding zones.
  3. Process of incinerating waste material, which comprises preliminarily warming, drying, and burning the material by passing the same through a plurality of zones in succession, effecting said burning operation in the presence of a countercurrent stream of preheated air together with gaseous products of combustion evolved from the burning material, withdrawing said stream from said zones at a point prior to its passage into the preliminary warming zone or zones, bringing said withdrawn stream into heat exchanging relationship with a supply of air to provide said preheated air, thereafter passing at least a part of said withdrawn stream through the warming zone or zones in contact with the material therein to heat the latter, and then discharging such part from said warming zone or zones independently of the above mentioned withdrawal of said stream from succeeding zones.
  4. Apparatus for incinerating waste material, comprising a furnace having a plurality of superposed hearths including an upper hearth or hearths for preliminarily warming and drying the material and a lower hearth or hearths for burning the material, means for feeding the material on to the top hearth, rabbling means cooperating with each of the hearths for periodically agitating and advancing the material over each hearth and gradually from hearth to hearth down through the furnace, a recuperator, means for conducting a supply of air through said recuperator and into the lower part of the furnace to provide preheated air for supporting combustion therein, means for withdrawing from the furnace hot gaseous products of combustion evolved at the burning hearth or hearths and passing such products through said recuperator

in heat exchanging relationship with said air, means for thereafter passing said products over the material on said upper hearth or hearths for providing heat to warm and dry the material thereon, while further reducing the temperature of said products, and means for then discharging said products from said upper hearth or hearths independently of the above mentioned withdrawal of the hot gaseous products from the furnace.

10 5. Apparatus for incinerating waste material, comprising a furnace having a plurality of superposed hearths including an upper hearth or hearths for preliminarily warming and drying the material and a lower hearth or hearths for

15 burning the material, means for feeding the material onto the top hearth, means for advancing the material over each hearth and from hearth to hearth down through the furnace, a recuperator, means for withdrawing hot gaseous products of combustion from the furnace at a point adjacent or above the upper zone of burning, and passing such products through said recuperator, means for conducting a supply of air through said recuperator in heat exchanging relationship

20 with said products and thence into the burning zones of the furnace, conduits provided with adjustable means for conducting predetermined portions of said gaseous products, after passage through said recuperator, over the material being

25 dried and warmed on said upper hearths, and means for then discharging said products from said upper hearths independently of the above mentioned withdrawal of the hot gaseous products from the furnace.

30 6. Apparatus for incinerating waste material, comprising a furnace having a plurality of superposed hearths including upper hearths for preliminarily warming and drying the material and a lower hearth or hearths for burning the material, means for feeding the material on to the top hearth, means for advancing the material over each hearth and from hearth to hearth down through the furnace, means for causing hot gaseous products of combustion to pass counter

35 current to the material over said burning hearth or hearths and out of the furnace at a point adjacent or above the upper zone of burning and for causing the vapor evolved from the material on the drying hearths to pass along the, path of travel of the drying material and thence out of the furnace, a recuperator, means for conducting said gaseous products and vapor after leaving the furnace through said recuperator in heat exchanging relationship with a supply of

40 air for preheating said air, means for conducting said preheated air over the material on the burning hearths of the furnace, conduits for conducting a portion of said gaseous products and vapor after leaving the recuperator into the upper

45 part of the furnace to provide heat for warming and drying the material therein, and means for then discharging said portion of the gaseous products and vapor from the upper part of the furnace independently of the withdrawal of the

50 65 hot gaseous products from the furnace.

7. Apparatus for incinerating sewage material, comprising a furnace having a plurality of superposed hearths including upper hearths for preliminarily warming and drying the material and lower hearths for burning the material, means for feeding the material on to the top hearth, rabbling means cooperating with each of the hearths for periodically agitating and advancing the material over each hearth and gradually from hearth to hearth down through the furnace, a recuperator, means for conducting a supply of air through said recuperator and into the lower part of the furnace to provide preheated air for supporting combustion therein, and whereby said air together with gaseous products of combustion evolved from the burning material then pass countercurrent to the passage of the material over the burning hearths, means for withdrawing said products from the furnace at a point after their passage over an upper burning hearth and before such products pass into the presence of the material on the uppermost warming and drying hearths, means for passing said withdrawn products through said recuperator in heat exchanging relationship with said air, and means for thereafter passing at least a substantial part of said products over the material on said upper warming and drying hearth or hearths to warm and dry the material thereon.

8. Apparatus for incinerating sewage material, comprising a furnace having a plurality of superposed hearths including upper hearths for preliminarily warming and drying the material and lower hearths for burning the material, means for feeding the material on to the top hearth, rabbling means cooperating with each of the hearths for periodically agitating and advancing the material over each hearth and gradually from hearth to hearth down through the furnace, a recuperator, means for conducting a supply of air through said recuperator and into the lower part of the furnace to provide preheated air for supporting combustion therein, and whereby said air together with gaseous products of combustion evolved from the burning material then pass countercurrent to the passage of the material over the burning hearths, means for withdrawing said products from the furnace at an upper burning hearth before such products pass into the presence of the material on the upper warming and drying hearths, means for passing said withdrawn products through said recuperator in heat exchanging relationship with said air, means for thereafter passing at least a substantial part of said products over the material on said upper warming and drying hearth or hearths to warm and dry the material thereon, and means for causing the gaseous products and vapor evolved at the warming and drying hearths to pass downwardly and along the path of travel of the drying material on the warming and drying hearths and thence out of the furnace at a point adjacent the upper burning hearth.

FREDERICK B. SCHILLING. 65
